UNITED STATES PATENT OFFICE.

ELMER A. ERMOLD, OF PHILADELPHIA, PENNSYLVANIA, ASSIGNOR TO WIRT COMPANY, OF PHILADELPHIA, PENNSYLVANIA, A CORPORATION OF MAINE.

DESIGN FOR A LAMP FIXTURE.

Application filed March 29, 1926. Serial No. 17,095. Term of patent 7 years.

To all whom it may concern:

Be it known that I, ELMER A. ERMOLD, a citizen of the United States, residing at 4914 Green Street, in the city and county of Philadelphia and State of Pennsylvania, have invented a new, original, and ornamental Design for Lamp Fixtures, of which the following is a specification, reference being had to the accompanying drawing, forming part thereof.

Fig. 1 is a front view of an electric lamp fixture embodying my design;

Fig. 2 is a side view of the same.

I claim:

The ornamental design for lamp fixture as shown.

ELMER A. ERMOLD.
